SURF BOARD WITH AN EXTENSIBLE
KEEL MEMBER

Doty M. Steele, Los Angeles, Calif.

Application May 7, 1949, Serial No. 91,957

6 Claims. (Cl. 9—11)

1

My invention relates to surf boards, particularly of the type powered by an internal combustion engine and the structure herein disclosed in an improvement on the Power Driven Surf Board forming the subject matter of United States Letters Patent Number 2,451,781, issued to me, October 19, 1948.

Among the principal objects of my present invention are to provide a surf board hull of novel structure and which is divided by bulk heads into air chambers, also wells or compartments for the extensible keel member and the lower portion of the engine housing and propeller, to provide improved means for mounting the engine so that it may swing on a horizontal axis and thereby elevate the lower portion of the driving shaft and propeller so to avoid striking an object floating on the surface of the water, or from making contact with the ground when approaching the shore, to provide the surf board with an extensible keel member and means for raising and lowering same, so as to materially increase the control of the board while it is in use, to provide simple and convenient means for the rider of the board to have greater control of the driving motor and to provide automatically acting means for cutting off the supply of air to the carburetor of the motor in the event that the board should capsize while in service.

With the foregoing and other objects in view, my invention consists in certain novel features of construction and arrangement of parts which will be hereinafter more fully described and claimed and illustrated in the accompanying drawings, in which:

Fig. 1 is a vertical section taken lengthwise through the center of my improved surf board.

Fig. 2 is a plan view of the surf board with parts thereof broken away and in horizontal section.

Fig. 3 is a horizontal section taken on the line 3—3 of Fig. 1 and looking into the well which accommodates the propeller, the propeller shaft and its housing.

Fig. 4 is an enlarged detail section taken on the line 4—4 of Fig. 2.

Fig. 5 is an enlarged plan view taken looking in the direction indicated by arrow 5 in Fig. 1 and showing certain of the engine controls.

Fig. 6 is a detail section taken on the line 6—6 of Fig. 5.

Fig. 7 is an enlarged vertical section taken on the line 7—7 of Fig. 8.

Fig. 8 is an elevational view partly in cross section, of the engine throttle mechanism and the ignition control system.

2

Fig. 9 is a detail section taken on the line 9—9 of Fig. 8.

Fig. 10 is a detail section of the automatic valve for controlling the inlet of air to the carburetor.

Fig. 11 is a section similar to Fig. 10 and showing the carburetor air inlet valve inverted and closed.

Fig. 12 is an enlarged vertical longitudinal section taken through the rear portion of the hull of the surf board and showing the improved extensible keel member.

Fig. 13 is a horizontal section taken on the line 13—13 of Fig. 12.

Fig. 14 is an enlarged vertical section taken on the line 14—14 of Fig. 12.

Referring by numerals to the accompanying drawings, which illustrate a preferred embodiment of my invention, 10 designates the hull of the surf board, same comprising a deck 11, side walls 12, rear end walls 13 and bottom 14 having an upwardly curved front end 15.

Spaced parallel partitions 16 extend from front to rear of the hull adjacent the center thereof and transverse bulkheads 17 disposed between sides 12 and said partitions, provide a series of air chambers 18.

Formed through the bulk heads 17 are apertures 19 to enable air to circulate through the chambers 18 which air is admitted through breather pipes 20 which enter the forward pair of chambers 18 as seen in Figs. 2 and 4. Further, the apertures 19 permits any water that may leak into chambers 18 to pass to the rear pair of chambers when the board is stood upright on its rear end, and discharge through apertures 21 in rear wall 13, which apertures are normally closed by corks 22.

Equalizing the air pressure within chambers 18 with the atmosphere, prevents partial vacuum from being developed within the chambers and which condition might draw water through any minute apertures or cracks which may occur in that portion of the surf board below the surface of the water.

The chambers 18 on one side of the hull are entirely separate from those on the other side and thus, if one side or corner of the hull is damaged to such a degree as to leak water, the other side or sections remains water tight and thereby provides sufficient buoyancy to prevent sinking of the surf board and its engine.

On deck 11 near the corners thereof are blocks 23 to which are attached rings or loops 24 of rope or cable which serve as handles for riders getting on or off the surf board or for shifting the

position thereof, while near a dock, float or other landing place.

In the forward portion of the space between partitions 16, a transverse wall 25 and a curved portion 26 of bottom 14 provide between them, a well or pocket 27, adapted to receive the lower portion of the propeller shaft, its housing 28 and the propeller 29 when the engine 30 swings from its normal upright position forwardly as shown by dotted lines Fig. 1, thus protecting said shaft, housing and propeller from being damaged as a result of striking a floating object, or the ground adjacent a shore landing.

Engine 30 is arranged to swing in horizontal bearings 31, on brackets 32 and the latter being detachably clamped on the upper end of transverse wall 25.

The opening into well 27 through deck 11 to the sides of and rearwardly from housing 28, is closed by a flexible flap 33, preferably rubber, which permits the housing to swing upward and this flap normally preventing water from splashing upward through said well onto the deck.

To prevent water from entering the air intake to the carburetor of the engine in the event that the board is overturned, a right angle fitting 34 is fitted onto the air intake 35 (see Figs. 10 and 11) with a perforated open ended nipple 36 connected to the vertical leg of said fitting.

A ball valve 37 is loosely retained in nipple 36 by a cross pin 38 and when the board is overturned, ball 37 will by gravity move downward in said nipple and rest on the seat formed by the end of fitting within the nipple (see Fig. 11).

Mounted on the upper portion of the motor housing 30 is a horizontally disposed frame 39 held in position at the rear of said housing by a cross strap 40. This frame provides a ground for the electrical connections associated with the motor and its ignition system. A plate 41 on the rear left hand end of frame 39 carries the engine throttle and ignition system control mechanism, same including a shaft 42 operating in bearings 43 and said shaft being provided with a universal joint 44 so as to permit its outer end portion 45 to move for a limited distance through a horizontal slot 46 in the outer one of the bearings 43. The outer end member 47 of the universal joint 44 carries a contact stud 48 adapted, when shaft member 45 moves to one end of slot 46, to contact a ground stud 49 thus providing an auxiliary or added connection for the motor circuit when same is closed.

The outer end of shaft member 45 carries a cross arm 50 to the ends of which are secured the ends of engine operation control cables 51. The inner end of shaft carries a disc 52 of insulation with a spiral spring 52a arranged between said disc and plate 41, to yieldingly hold said disc and the shaft 42 in normal "out-of-service" positions and seated in the periphery of said disc is a conductor plate 53, in the center of which is a recess containing a block of insulation 54. A brush contact 55 is mounted upon and insulated from plate 41 with the free end of said brush in engagement with insulation block 54 when the circuit to the ignition coil is open.

Conductors 56 and 57 connect contact plate 53 and brush 55 respectively with the ignition coil of the engine.

A flexible connection 58 is arranged between disc 52 and a crank arm 59 carried by the engine throttle actuating shaft 60 (see Figs. 7 and 8). A cable 39a extends rearwardly from the rear right hand end of frame 39 and is adapted to be

grasped by the hand and thereby render more steady, the rider's position while standing on the rear portion of the board.

Spaced side walls 61 in the rear central portion of hull 10 provide a narrow pocket 62, open at bottom and rear for the extensible keel member 63 and for the operating wedge 64.

The extensible keel member is a substantially rectangular plate or panel pivoted near its front lower corner on a pin 65 seated in walls 61 and arranged in the lower front end of pocket 62 is a block 6 having an inclined face 67 which acts as a stop to limit the downward swinging movement of said keel member.

Formed in the upper forward end of keel member 63 is a substantially triangular notch 68, having an inclined forward edge 69 with a small notch 70 at the rear upper end of said notch 68 and with a small notch 71 at the upper forward end of the inclined edge 69. Formed at the upper forward corner of wedge 64 is a rounded projection 64a of such size as to occupy notch 71 in keel member 63. When the keel member is elevated, the rounded forward end 64a of the wedge member engages in notch 71, thereby practically locking the keel member against downward movement and when lowered the keel member is held in such position by the engagement of the lower rear end corner of wedge, in notch 70. Notch 68 is slightly longer than wedge 64.

Secured to the ends of wedge 64 are the ends of a cable 72 which, at the ends of pocket 62, pass upward through apertures 73 in deck 11 and the ends of said cable above the deck are secured to a block 74, arranged for sliding movement on top of the deck and adapted to be engaged by the surf board rider's foot and moved forwardly or rearwardly to move wedge 64 and thereby swing keel member so as to raise or lower same. (See Fig. 12.) To lower the keel member, block 74 is moved forwardly thereby moving wedge 64 rearwardly so as to shift the rounded forward corner 64a of said wedge out of notch 71 and causing the rear end of the wedge to engage the rear edge of notch 68 with the rear upper corner of said wedge bearing in notch 70 and thus swinging the keel member to its lowermost position as shown by dotted lines in Fig. 12.

The downward movement of the keel member is stopped by the engagement of the front edge thereof against inclined face 67 of block 66. A reverse or rearward movement of foot engaged block 74 reverses the actions just described and raises the keel member into pocket 62. If desired a rider's seat 75 may be detachably mounted on the deck just in front of the keel member actuating block 74.

The gas throttle of the engine that drives the propeller, as well as the ignition coil are controlled by means of the cables 51, which when properly manipulated, swing cross arm 50 to rock shaft 42 thus partially rotating disc 52 against the tension of spring 52a, thereby actuating arm 59 on throttle actuating shaft 60 and simultaneously energising the ignition circuit through brush 55 and contact plate, with a secondary circuit energisation effected through contacts 48 and 49.

Thus, it will be seen that I have provided an improved motor driven surf board of simple, practical structure which includes an extensible keel member with simple and efficient operating means therefor and the driving motor of the surf board being mounted so as to be readily swung upward into a pocket in the underside of the hull structure and said motor being provided with simple

and readily operable ignition and throttle control means.

Minor changes in the size, form and construction of the various parts of my improved motor driven surf board may be made and substituted for those herein shown and described without departing from the spirit of my invention, the scope of which is set forth in the appended claims.

I claim as my invention:

1. In a surf board, a hull, an extensible keel member pivotally mounted for vertical swinging movement in the rear portion of said hull and a substantially triangular member arranged for sliding movement above said extensible keel member and bearing upon the upper forward corner thereof for raising and lowering same. 15

2. The surf board as set forth in claim 1, with pedally operated means operatively connected to said sliding member for actuation thereof.

3. In a surf board, a hull, an extensible keel member mounted for vertical swinging movement in the rear lower portion of said hull and a wedge arranged for sliding movement above said keel member and operatively associated therewith for raising and lowering same.

4. The surf board as set forth in claim 3, with means operatively connected to said wedge for actuation thereof a portion of which wedge sliding means is above said surf board.

5. In a surf board, a hull, an extensible keel member pivoted for vertical swinging movement in the lower rear portion of said hull, said keel

member being provided in its upper forward corner with a substantially triangular notch and a substantially wedge shaped member mounted for limited sliding movement in said notch for raising and lowering said extensible keel member.

6. The surf board as set forth in claim 5, with small rounded notches at both ends of the triangular notch in said keel member for accommodating the ends of said wedge shaped sliding member at the ends of its travel.

DOTY M. STEELE.
